UNITED STATES PATENT OFFICE.

ROBERT M. DIXON, OF EAST ORANGE, NEW JERSEY, ASSIGNOR TO THE
SAFETY CAR HEATING AND LIGHTING COMPANY, OF NEW JERSEY.

LIGHTING APPARATUS.

SPECIFICATION forming part of Letters Patent No. 643,814, dated February 20, 1900.

Application filed December 7, 1897. Serial No. 661,085. (No model.)

To all whom it may concern:

Be it known that I, ROBERT M. DIXON, a citizen of the United States, residing at East Orange, State of New Jersey, have invented 5 new and useful Improvements in Lighting Apparatus, of which the following is a specification.

My invention relates to the production of light, and is more specifically designed to produce a lamp for lighting cars or other apartments in which two or more sets of light-giving apparatus are so combined that they may be used alternately or in conjunction, while the exterior of the apparatus will present the 15 appearance of and is, in fact, a single unitary lamp structure.

In the lighting of the interior of railway-cars, for which my invention is more specifically adapted, it is sometimes desirable to use 20 the electric current for lighting where the cars are coupled up in a train employing electric lighting, or a source of electric current is otherwise provided. At the same time it is important to have a separate means of producing light which may be supplied by gas—for instance, when no source of electricity is 25 at hand. Moreover, the double lamp is advantageous even where both gas and electricity are available, since one may be used 30 to supplement the other in case of a breakdown.

The preferred form of my invention is shown in the accompanying drawing, in which is illustrated in section a lamp attached to the 35 roof of a car or other compartment.

1 represents a portion of the ceiling or roof structure of the car, to which the ring of metal 2 is fastened by screws 3 3 or other convenient fastening means. On the fixed ring is 40 hinged the ring 4 in the usual manner, and to this is attached the bowl 5 of the lamp in any convenient way, as by means of the outwardly-turned lip 6, held between the two packing-rings 7 and 8, which in turn are held 45 in place by the overhanging metal ring 9. This metal ring 9 may be removed by taking out the short screws 9^a 9^a, shown at either side of the drawing. The glass bowl 5 can then be removed. Within the bowl 5, which is of 50 glass, is supported any suitable form of gas or other burner 10. I have illustrated a cir-

cular burner supplied by the central feed-pipe 12, having the deflecting-shields 13 and 14 and the chimney 15. This burner is supported from the spider 16, fixed in the circular opening 17 in the roof. 55

18 is any convenient form of wind-deflecting hood for the lamp.

The gas-supply pipe 19 has a valve 20, the spindle of which, 21, projects down through 60 the roof and has a handle 22, by which the valve may be operated from the interior of the car. I preferably mount this valve on a cylinder 23, which is cast integrally with the valve-casing and within which is the concentric sleeve 24 for the valve stem or spindle. This protecting shell or cylinder passes down through the ceiling and opens into the space confined by the lamp-bowl and its supporting-rings. 70

Supported on the spider 25 is the reflector 26, having its under side glazed with porcelain or other refractory light-reflecting coating. Through the reflector a number of openings 27 27 are formed and through these project electric lamps 28 28, which are attached to the car-ceiling and connected to the main-circuit electric wires. (Not shown.) 75

The mode of operating my invention is evident from the foregoing description. When 80 the car is provided with or connected to a source of electric current, the electric lamps 28 28 are caused to glow, and light is thrown down into the car by the reflector 26. When no electric current is obtainable, the valve 20 85 is opened and the gas-burner 10 is lighted, the same reflector acting to diffuse the light through the car.

A special advantage of the valve construction illustrated is that any leakage about the 90 valve-stem is conducted by the cylinder or shell 23 down to the inclosed space of the lamp, and such gas so leaking from the valve is carried up by the draft of the lamp to the hood 18 and discharged into the open air, 95 thus preventing the offensive smell of such gas from disturbing the occupants of the car.

The advantages of the apparatus as a whole consist in the combination of two sets of light-giving apparatus in operative relation to one 100 reflector and embodied in a single lamp structure.

Having therefore described my invention, what I claim as new, and desire to protect by Letters Patent, is—

1. In a lamp structure, a concave reflector having a central opening and a series of lateral openings, a gas-burner located under the reflector, a series of electric lamps projecting inwardly through the lateral openings in said reflector, and a globe inclosing both the gas-burner and the electric lamps.
2. In combination with the inclosing globe of a gas-lamp, and the gas-supply pipe and valve therein, of a valve-stem projecting through the outer shell of the lamp structure, and the extension to the valve-casing surrounding said valve-stem and opening into the inclosing globe, substantially as described.

3. The combination of the car-ceiling the gas-supply pipe and valve above said ceiling, the inclosing lamp-globe fastened to the under side of said ceiling, the valve-stem extending down through said ceiling and lamp-globe, and the shell surrounding said stem, which shell is cast integrally with the valve-casing, and extends through the car-ceiling and opens into the inclosure within the lamp-globe, substantially as described. 20 25

In testimony whereof I affix my signature in the presence of two witnesses.

ROBERT M. DIXON.
